(57) **CLAIM**

The ornamental design for a channel, as shown and described.

DESCRIPTION

FIG. 1 is an enlarged a front, top, and end view of a channel that has the design.

FIG. 2 is top plan view of the channel.

FIG. 3 is an end view of the channel.

FIG. 4 is a front elevation.

FIG. 5 is an opposite end view; and,

FIG. 6 is a bottom view. The back is also planar, and looks the same as the bottom.

The width of the channel may vary.

The channel is used as a post for fencing or screens, with the fence or screen elements fitting into the channel in the front. The channel can also be used as a rail or a picture frame.
